UNITED STATES PATENT OFFICE.

RUSSELL R. EVANS, OF TACOMA, WASHINGTON.

CONTAINER AND CLOSURE THEREFOR.

Application filed January 6, 1923. Serial No. 611,101.

To all whom it may concern:

Be it known that I, RUSSELL R. EVANS, a citizen of the United States, residing at Tacoma, in the county of Pierce and State 5 of Washington, have invented new and useful Improvements in Containers and Closures Therefor, of which the following is a specification.

My present invention has reference to 10 containers for foodstuffs and the like and closures for such containers, and has particular reference to a construction by which the closure engages the container in a manner to hermetically seal the same and yet 15 permit the removal and replacing of said closure without damage thereto so that quantities of the contents of the container may be used as occasion requires without liability of spoiling of the remainder of the 20 contents, and also wherein the device may be used continuously for substances other than the original contents of the container.

It is a further object to produce a can 25 or similar container having its mouth formed with an outwardly directed bead and a cover therefor having its outer edge rolled to provide a lip, the inner wall of the lip being arranged at a slight acute angle with respect to the body of the closure, and the outer 30 curved wall of the said lip being rounded inwardly and being of a less length than the inner wall, these walls exerting a pressure toward each other to afford an impinging engagement with the lip and with the inner 35 face of the mouth of the can, while in the lip there is arranged a plastic substantially non-porous gasket designed for lateral expansion when the cover is forced over the beaded mouth of the container to assist in 40 hermetically sealing the container.

A further object is to produce a container and a cover therefor, said container having a rolled lip providing an outstanding bead, the closure therefor having its body portion flat and the edge thereof formed with an 45 upwardly directed rolled lip having therein a plastic compressible gasket designed when the lip is arranged over the bead to be expanded laterally, and wherein the engagement between the inner and outer walls of the lip and the mouth and bead of the closure is such that a pressure exerted upon the closure from the interior of the container will cause the rolled lip thereof to 50 move into tighter engagement with the bead of the container so that liability of the re-

moval of the closure from the container by such cause is effectively obviated.

It is a still further object to produce a container which may be in the nature of a 60 can that has its mouth rounded outwardly and downwardly to provide a bead, and a closure having its body in the nature of a disk-like spring metal member whose periphery is rolled to provide a lip, the inner 65 wall of which being arranged at a slight inward angle with respect to the body of the closure, whose upper wall is rounded, and whose outer wall is curved for frictional contact with the outer curved surface of 70 the beaded mouth of the container, said last mentioned wall of the lip having at spaced intervals inwardly directed spring fingers that contact with the under face of the lip and also with the outer side of the container 75 and consequently are arranged inwardly of the outer wall of the lip, said fingers assisting in sustaining the closure on the container and to prevent the removal of said closure until the said fingers are bent or sprung out 80 of contacting engagement with the lip and inner wall of the container, while between the lip and bead there is a gasket designed for lateral compression when the closure engages the mouth of the container and exerts 85 an impinging action between the inner wall of the container and the outer wall of the lip thereof.

To the attainment of the foregoing and other objects which will present themselves 90 as the nature of the invention is better understood, reference is to be had to the drawing which accompanies and which forms part of this application.

In the drawing:—

Figure 1 is a perspective view of a container and closure in accordance with this invention.

Figure 2 is an approximately central vertical longitudinal sectional view there- 100 through.

Figure 3 is a greatly enlarged sectional view taken through a portion of the closure and one side of the container.

Figure 4 is a view substantially similar 105 to Figure 3 but showing the closure engaging the beaded mouth of a glass or porcelain container.

The container 1 is in the nature of an ordinary tin can which is round in plan. 110 The can 1 has its mouth rounded outwardly, as at 2 and extended at an inward curvature;

as at 3. The elements 2 and 3 provide a continuous bead for the mouth of the can, and by reference, especially to Figure 3 of the drawings it will be seen that the lower wall 6 of the bead is out of contact with the side of the can 1. As stated, the can is constructed of metal and therefore the outer wall 3 of the bead has an inherent resiliency so that the same will have a slight tendency 10 to spring in an outward direction.

The closure includes a flat disk-like body 4 provided, from its under face with one or a plurality of continuous outwardly bulged portions 5. At its periphery the body 4 of the closure is bent upwardly at a slight inward or acute angle with respect to the body 4. This angle wall is indicated, in the drawing, by the numeral 6. The wall 6 merges into an outwardly rounded portion 7 20 that has a downwardly and an inwardly curved extension 8. The walls 6, 7 and 8 provide the closure 7 with a lip.

Before being arranged upon the bead provided at the mouth of the container there is 25 inserted in the lip of the closure a plastic sealing element composed of rubber and other suitable materials to provide a continuous gasket 9. When the rolled lip of the closure is forced over the bead of the can or container 1 the walls 6 and 8 of the lip will exert an impinging action upon the inner wall of the mouth and the outer wall of the bead. This causes the outer rounded wall of the lip to force the gasket against 30 the bead of the closure to laterally expand the gasket therebetween, causing the said gasket to materially assist in hermetically sealing the closure. The wall 6 of the lip of the closure is in frictional engagement with 35 the inner wall at the mouth of the container only at the inner portion thereof, or the portion thereof at and slightly adjacent to the juncture of the wall with the body of the closure, while the rounded wall 8 of the lip 40 has only its inner end portion in contacting engagement with the outer inwardly curved wall 3 of the bead. The contacting engagement between these elements of the closure and the container and its lip are not at directly opposite points, as will be clearly 45 seen by reference to Figure 3 of the drawing. The impinging parts of the wall 6 against the inner wall or mouth of the container 1 and the outer inwardly curved wall 8 of the lip against the inwardly curved wall 3 of the bead is such that should a pressure from the interior of the container 50 be exerted upon the closure 4, (by gases from the foodstuff arranged in the containers or from other causes) such pressure will have a tendency to contract or bulge outwardly the body 4 of the closure and cause the wall 8 of the lip to travel further in a downward direction and over the wall 8 of the bead of the container, with the result that any in- 55

ward pressure against the closure serves only to create a tighter frictional engagement between the lip thereof and the mouth and the bead of the container. By providing the continuous outstanding depressions 5 greater 70 space for expanding gases from foodstuff is provided, and consequently the liability of such pressure influencing the container as above described will be materially lessened. 75

The wall 8 of the bead of the closure is, at determined intervals, integrally formed with inwardly rounded extensions in the nature of fingers 9'. The fingers are disposed below and in the path of contacting engagement with the bead of the container and in 80 addition to this are in contact with the side wall of the said container. These spring fingers being arranged inward of the lip of the closure and the bead of the container prevent accidental separation of these parts 85 as the said fingers are not liable to contact when the cans or containers are handled, which would be true should the fingers project directly downwardly from the lower edges of the bead. Also it is necessary that 90 at least one of the fingers 9' be sprung outwardly from the container and a pressure exerted thereagainst before the closure can be removed from the container. The container may be not only used for original contents but may be from time to time used as 95 receptacles for other foodstuffs or the like, with the result that a single container and cover therefor may be employed in a household for an indefinite period of time. 100

In Figure 4 of the drawing I have illustrated a closure constructed exactly as heretofore described, but the rolled lip thereof is brought over the outwardly extending bead 10 on a glass or porcelain container 11. 105 The impinging action between the inner and outer walls of the lip of the closure with respect to the mouth and bead of the receptacle or container 11 is exactly similar to that previously described, although the impinging action between the inner and outer walls of the lip is not assisted by the spring outer wall afforded by the bead of a metal container. The fingers 12 on the outer wall of the lip 13 of the closure 14, disclosed in 110 the said Figure 4 are rounded inwardly to contact with the under face of the bead 10, and with the outer wall of the container or receptacle 11 so that the said fingers 12 are held inwardly with respect to the lip and 115 bead to prevent the accidental contact thereof. 120

From experience I have found that I can manufacture my can and closure more cheaply than any other self-closing can with 125 which I am acquainted, and I have found that the sealing engagement between the can and closure is such as to permit of foodstuffs whose nature is such that the same could not heretofore be retained against 130

spoilage by any self-sealing can. I have further found that my closure may be successfully employed upon ordinary glass or porcelain containers, as disclosed in Figure 5 4 of my drawing, so that such containers, usually destroyed after the original contents thereof are removed, may be employed indefinitely as containers for similar or other materials, and will hermetically seal the 10 same as long as the closure is positioned thereon.

Having described the invention, I claim:—

1. A container whose inner wall is straight and which has an outwardly beaded mouth 15 whose outer wall is arranged at an inward curvature, and a spring metal closure for the container, comprising a body having a lipped edge defining an inner slightly inwardly inclined wall, and an upwardly rounded top wall which merges into an inwardly rounded outer wall whose edge is disposed outward of the juncture of the inner wall of the bead with the body of the 20 container, a gasket in the lip, said lip designed to be forced over the beaded mouth of the closure to compress the gasket against the top wall of the bead and to cause the inner wall of the lip at its juncture with the body to frictionally engage the inner wall 25 of the container, and the outer rounded wall of the lip to have its inner end portion likewise frictionally engage with the outer wall of the bead, and the said engaging portions of the lip exerting an impinging action toward each other.

2. A container having its mouth formed with an outwardly directed bead whose top is rounded and whose outer wall is disposed at an inward curvature to the body of the 40 container, and a spring metal closure for the container, comprising a disk-like body peripherally formed with an upstanding portion defining an inner inclined wall whose outer end is rounded outwardly and from thence 45 rounded inwardly, a semi-plastic continuous gasket in the lip, the inner wall of the lip being of a greater length than the outer wall thereof, and both walls of the lip designed to exert an impinging action against 50 the inner wall of the container and the bead thereof when the cover is forced over the beaded mouth of the container to also compress and laterally expand the gasket, and the outer wall of the lip having spaced 55 spring fingers disposed beneath the bead of the container and in contact with the outer wall of said container.

3. A container in the nature of a tin can whose inner wall is straight and whose 60 mouth is rounded outwardly and curved in-

wardly at its side to provide a bead, the edge of the bead being spaced from contact with the body of the can, a closure of spring metal including a flat disk-like body having its periphery formed with a slightly inwardly inclined outwardly directed wall merging into a rounded portion that terminates in a downwardly arranged inwardly directed curved outer wall to provide a lip, the outer wall of the lip being of a less 65 length than the inner wall thereof, said lip designed to receive a gasket therein and to compress the same over the outer rounded wall of the bead of the container when the lip of the closure is forced over said bead, 70 and when so positioned the inner inclined wall of the lip at and adjacent to its juncture with the body thereof exerts an impinging action upon the straight inner wall of the closure, while the outer side wall of the 75 lip exerts a similar pressure against the outer wall of the bead, and the said wall of the bead exerts a like pressure against the said outer wall of the lip.

4. A container in the nature of a tin can whose inner wall is straight and whose mouth is rounded outwardly and curved inwardly to provide a bead, the outer edge of which being disposed away from contact 80 with the side of the can, and a closure for 85 the can, comprising a disk-like body having a peripheral lip defining an inner slightly inwardly inclined wall, an outwardly rounded top which merges into an inwardly rounded outer wall and which terminates 90 outward with respect to the juncture of the inner wall of the bead with the body of the closure, and inwardly rounded fingers extending from the outer wall of the lip, said 95 lip designed to receive a gasket therein 100 which is adapted to be compressed against the rounded wall of the bead when the lip is forced over the bead in the application of the closure, and when in such position the inner angle wall of the bead at and adjacent 105 to its juncture with the body of the closure exerts a frictional engagement against the inner straight wall of the container, the outer rounded wall of the lip contacting with and exerting an inward pressure 110 against the lip, the outer wall of the bead exerting a like pressure against the outer wall of the lip, and the spring fingers being brought to contact with and having their contacting portions arranged in a plane 115 with the outer wall of the container and below the contacting engagement of the inner wall of the lip with the container.

In testimony whereof I affix my signature.

RUSSELL R. EVANS.
